UNITED STATES PATENT OFFICE

164,099

COMBINED CHAIR AND TRAY

Christian E. Choate, Los Angeles, Calif., assignor
of one-half to Cliff May, Los Angeles, Calif.

Application May 8, 1950, Serial No. 9,790

Term of patent 7 years

(Cl. D15—8)

To all whom it may concern:

Be it known that I, Christian E. Choate, a citizen of the United States and a resident of Los Angeles, California, have invented a new, original, and ornamental Design for a Combined Chair and Tray, of which the following is a specification, reference being had to the accompanying drawings, forming part thereof.

Referring to the drawings:

Figure 1 is a perspective view of a combined chair and tray, showing my new design;

Figure 2 is a front elevation thereof;

Figure 3 is a side elevation of the chair shown in Figure 1, looking toward the tray side of the chair; and

Figure 4 is a top plan view of the combined chair and tray shown in Figures 1, 2 and 3.

I claim:

The ornamental design for a combined chair and tray, as shown.

CHRISTIAN E. CHOATE.
